CLAIM

The ornamental design for a surgical control apparatus, as shown and described.

DESCRIPTION

FIG. 1 is a perspective view of a surgical control apparatus showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIGS. 8 and 9 are additional perspective views thereof.

The surgical control apparatus illustrated in FIGS. 1-9 may be, for example, a surgical control apparatus for lung surgery.

The broken lines in FIGS. 1-9 illustrate unclaimed portions of the surgical control apparatus and form no part of the claimed design.
